UNITED STATES PATENT OFFICE.

ALBERT J. FORSETH, OF GRAND FORKS, NORTH DAKOTA, ASSIGNOR TO B. F. GILBERT,
OF FORT WORTH, TEXAS.

AUTOMATICALLY-ADJUSTABLE EMBROIDERY GUIDE.

Application filed May 5, 1924. Serial No. 711,082.

My invention relates to sewing machine attachments and more particularly to an embroidering device; and the object is to provide a simple device which may be attached to the 5 presser-foot of a sewing machine and which is adjustable to any presser foot of ordinary construction and by which embroidering can be speedily and efficiently accomplished.

Other objects and advantages will be fully 10 explained in the following description and the invention will be more particularly pointed out in the claim.

Reference is had to the accompanying 15 drawings which form a part of this application.

Fig. 1 is a perspective view of a presser foot and the embroidering device attached thereto. Fig. 2 is a side elevation of the same. Fig. 20 3 is a front elevation of the same. Fig. 4 is a plan view of the same. Fig. 5 is a front elevation of the guide and holder.

Similar characters of reference are used to indicate the same parts throughout the several views.

25 The presser-foot 1 of ordinary type is shown in the drawings. The presser foot 1 has the usual long toe 2 and the short toe 3 and a slot 4. The attachment consists of a single piece of metal which is provided with 30 a clamping member 5 for engaging the longer toe 2 of the presser-foot. The attachment is preferably made of steel so that the clamping member 5 will engage a presser-foot of any ordinary construction, some presser-foot being larger or smaller than others. The at-

tachment is provided with a guiding member 6 for receiving the embroidery thread 7. The guiding member 6 is bent downwardly to form a groove 8 to receive the thread 7. Incidentally, the curved guide member 8 forms 40 an adjusting means to align the attachment with the slot 4 of the presser-foot. The attachment thus automatically adjusts itself to the presser-foot when it is placed on the longer toe 2. The thread will run through 45 the groove 8 and on through the slot 4 of the presser-foot. The attachment is provided with an additional guide finger 9 which forms an entrance throat for guiding the thread 7 into its place and this guide member 9 prevents displacement of the thread during 50 operation.

What I claim is—

An attachment for sewing machines comprising a thin metal body portion adapted to 55 extend across the bifurcation of the presser foot of a sewing machine on the upper side of the presser foot, a member on the under side of the body portion adapted to clamp on the under side of the presser foot, said body portion having a thread receiving groove extending across it on its upper side, which groove defines a rib on the under side of the body portion, said rib being adapted to extend into the bifurcation of the presser foot and a 60 tongue on the body portion extending cross- 65 wise of said groove.

In testimony whereof, I set my hand, this 27th day of March, 1924.

ALBERT J. FORSETH.
